UNITED STATES PATENT OFFICE.

HULBERT H. WARNER, OF ROCHESTER, NEW YORK.

DESIGN FOR A BOTTLE.

SPECIFICATION forming part of Design No. 14,425, dated November 20, 1883.

Application filed September 14, 1883. Term of patent 14 years.

to all whom it may concern:

Be it known that I, HULBERT H. WARNER, a citizen of the United States, residing in the city of Rochester, in the county of Monroe and 5 State of New York, have invented and produced a new and original Design for Bottles, of which the following is a specification, reference being had to the accompanying drawings, forming part hereof.

10 My design relates to that class of packing-vessels known as "glass bottles," for containing medicine or other fluid preparations.

Figure 1 is an upright view of the side of the bottle bearing the representation of a 15 canoe. Fig. 2 is an upright view of the opposite side, showing the depressed smooth surface; and Fig. 3 is a sectional view of the bottle as shown at the line *xx*.

Similar letters refer to similar parts throughout.

A is the body of the bottle, which is made with a rough surface, in imitation of a log of wood with its bark still attached.

B is the canoe, which is represented as being cut in the bark of the log on one side, and extends the full length of the body of the bottle.

C is the depressed smooth surface on the side of the bottle opposite the canoe, which 30 appears as if the bark of the log had been

blazed off, said depression extending not quite to either end of the body or log-part of the bottle.

D is the neck of the bottle, made with a broad rim at the top resembling a fungus or 35 toad-stool growing out of the end of the log below.

It will, of course, be understood that the depression C forms a suitable surface to which a label may be attached, in imitation of a sheet 40 of the bark of another kind of tree, or otherwise; also, that the convex surface of the fungus D may be utilized by covering it with a suitable label, and that the names of the contents and of the proprietor may be blown 45 in the body or log part of the bottle; but

What I claim, and desire to secure by Letters Patent of the United States, is—

The design for a bottle the body of which represents a log of wood with its bark attached, and having the representation of a canoe cut in the bark on one side and a portion of the bark blazed off on the opposite side, while its neck resembles a fungus growing out of the end of said log, substantially as 50 described and shown.

HULBERT H. WARNER.
